UNITED STATES PATENT OFFICE.

HUGH L. McDONALD, OF BRIDGEPORT, CAPE BRETON, NOVA SCOTIA, CANADA.

SLIDE-VALVE-OPERATING MECHANISM.

1,076,047.

Specification of Letters Patent. Patented Oct. 21, 1913.

Application filed April 19, 1913. Serial No. 762,325.

To all whom it may concern:

Be it known that I, HUGH L. McDONALD, a subject of the King of Great Britain, residing at Bridgeport, Cape Breton, Nova Scotia, Canada, have invented certain new and useful Improvements in Slide-Valve-Operating Mechanisms, of which the following is a specification, reference being had to the accompanying drawings.

10 This invention relates to slide valve operating mechanisms for engines and has for an object to provide an extremely simple mechanism of this character which will dispense with the usual eccentric on the engine shaft 5 and will employ a single slide valve stem and a single guide member having a cam slot receiving the stem, there being also a single connection between the engine pitman and the valve stem which connection moves 20 the valve stem in the cam slot whereby the travel is imparted to the slide valve.

A further object is to provide a novel valve stem which is so constructed as to impart the lap and lead to the slide valve.

25 A still further object is to provide a device of this character that will be inexpensive to manufacture and will not easily get out of order.

With the above objects in view the invention 30 consists of certain novel details of construction and combination of parts herein-after fully described and claimed, it being understood that various modifications may be made in the minor details of construction, 35 within the scope of the appended claims.

In the accompanying drawings illustrating 40 this invention: Figure 1 is a plan view, partly in horizontal section, showing the application of the invention. Fig. 2 is a side elevation of the parts shown in Fig. 1. Fig. 3 is a cross sectional view on the line 3-3 Fig. 2. Fig. 4 is a cross sectional view on the line 4-4 Fig. 2. Fig. 5 is a diagrammatic view showing the position of the parts 45 when the engine is on the back center. Fig. 6 is a diagrammatic view showing the position of the parts when the engine is on the forward center. Fig. 7 is a diagrammatic view showing the position of the parts when 50 the engine is on the top quarter. Fig. 8 is a plan view showing the valve rod formed to produce lap and lead. Fig. 9 is a side elevation of the rod shown in Fig. 8. Fig. 10 is an end elevation of the rod shown in Fig. 8. Fig. 11 is a plan view showing a modified form of the invention. Fig. 12 is a

side elevation, partly in vertical section of the parts shown in Fig. 11. Fig. 13 is a cross sectional view taken on the line 13-13 Fig. 12.

Referring now to the drawings in which like characters of reference designate similar parts, 10 designates a cylinder, 11 the pitman, and 12 the slide valve of an ordinary steam engine.

For brevity and clearness, all parts of the engine which are not necessary to promote the disclosure of the invention are not illustrated and will not be referred to in this description.

In carrying out my invention I provide a valve rod 13 which is turnably mounted in an opening in the slide valve 12 and is held against displacement by means of nuts 14 disposed at the ends of the valve, or otherwise. The rod is provided with a lateral offset 15 to dispose the intermediate portion 16 in close proximity to the pitman 11, the rod being offset outwardly as shown at 17 at the end of the intermediate portion to produce a crank, and then being terminally extended at a right angle to the crank to form a gudgeon 18.

A standard 19 is disposed stationary on the engine and is provided with a cam slot 20 which extends at an angle of about forty five degrees to the horizontal and receives the crank 17, the standard having an outwardly projecting arm 21 which is provided with an opening 22 that journals the gudgeon 18.

A pin 23 is threaded into the pitman and secured by means of a nut as shown, this pin carrying a forked head 24 which straddles the intermediate portion 16 of the valve rod and slides therealong during the travel of the pitman whereby the valve rod is raised and lowered with a resultant travel of the crank 17 longitudinally in the cam slot 20 whereby the travel of the slide valve is produced.

In the ordinary cam operated slide valve, the cam on the engine shaft must be turned around and adjusted to produce the proper lead when the slide valve has a known lap. To attain this end with the above described valve rod included in the subject-matter of this invention the valve rod must be bent up at *b* and down at *a* from the center line, see Figs. 8, 9 and 10. As an example, suppose that the slide valve has $\frac{3}{4}$ inch lap then the valve rod must be bent up at *b* and down

at a $\frac{3}{4}$ inch from the center line as best shown in Fig. 9. Where a slide valve is used that has no lap or lead a straight valve rod is used, that is all the parts of the rod lie in a single plane. Bending of the valve rod as above described to produce lap and lead does not lengthen the travel of the valve, as this bending of the valve rod is analogous to turning around and adjusting the eccentric 5

10 cam ordinarily used on engines.

In Figs. 5, 6 and 7 various positions of the slide valve and the corresponding positions of the valve rod are shown diagrammatically. Fig. 5 shows the positions assumed by the valve and valve rod when the engine is on the back center, while Fig. 6 shows the positions assumed by the valve and valve rod when the engine is on the forward center. Fig. 7 shows the positions assumed by the valve and valve rod when the engine is on the top quarter. In all of these figures it will be seen that the gudgeon 18 of the rod remains constantly on the center line of the valve while the travel of the forked 25 head of the pin carried by the pitman in its travel longitudinally of the rod moves the rod longitudinally in the cam slot 20 and opening 21 with a resultant reciprocation of the valve.

30 In practice it is not necessary that the standard 19 be used as the slot 20 may be formed in the casting of the waist or centerpiece of the engine, and the angle which this slot makes with the horizontal is varied 35 to suit various lengths of valve travel. As an example, when the slide valve has a travel of three inches, the slot will be disposed at an angle of forty five degrees to the horizontal while the pin 23 will have a vertical 40 reciprocatory movement of three inches.

In Figs. 11 to 13 inclusive a modification 45 of the invention is shown, which modification is designed for use in connection with slide valves which have a transverse travel 50 rather than a longitudinal travel of the cylinder.

In the modified form of the invention 55 designates the cylinder and 26 the slide valve which has a travel transversely of the cylinder. In this form of the invention the valve rod does not reciprocate so that the cam slot for this purpose is dispensed with, the valve rod merely being rocked by the up and down motion of the pin 27 carried as 60 above described by the pitman 28. The valve rod 29 is journaled in suitable stationary bearings 30 carried by the engine and is terminally equipped with a crank arm 31 that is pivotally connected at the free 65 end to the stem 32 of the slide valve 26. It will be apparent that upon rocking of the valve rod through the instrumentality of the pin carried by the pitman, the crank arm 31 will impart the necessary travel to the slide valve.

From the above description it will be seen that the slide valve operating mechanism constructed in accordance with my invention is extremely simple in construction, is formed of a few parts that will not easily get out of order, and may be applied to most reciprocating engines now in use without extensive alterations.

70 What is claimed, is:—

1. The combination with an engine slide valve and engine pitman, of a valve stem operatively connected to said valve, a pin carried by said pitman and having a sliding connection with said stem, and a stationary cam for imparting reciprocatory movement to said stem during actuation of the stem by 75 said pitman.

2. The combination with an engine slide valve and engine pitman, of a valve stem operatively connected to said valve, a pin carried by said pitman having a forked head loosely receiving said rod, means for journaling the free end of said rod, an offset formed in said rod, and a stationary member having a slot inclined at an angle to the horizontal receiving said offset, said slot coacting with said pin in imparting reciprocatory movement to said valve during travel of 80 said pitman.

3. The combination with an engine slide valve and engine pitman, of a valve stem connected at one end to said slide valve and having an offset formed therein to dispose the intermediate portion of said rod in close proximity to said pitman, a pin carried by said pitman having a sliding connection with said intermediate portion of said rod, a journal for the free end of said rod, there being a second offset in said rod parallel to the first offset and disposed between the latter and said journal, a stationary member having an inclined cam slot receiving said second offset, said slot coacting with said pin in imparting reciprocatory movement to said valve during actuation of said pitman.

4. The combination with an engine slide valve and valve seat and pitman, of an angularly bent rod having its intermediate portion offset from its ends and being rotatably connected at one end to said slide valve, a journal for the opposite end of said rod, a pin carried by said pitman and having a sliding connection with said intermediate portion and said rod and thereby serving to rock said intermediate portion, and means operatively connected to said angularly bent rod for reciprocating said rod simultaneously with the rocking motion thereof, whereby to reciprocate said valve both longitudinally and laterally of the valve seat.

5. The combination with an engine valve seat and a slide valve and pitman, of a rod rotatably connected at one end to said slide valve and having its other end mounted for 115 120 125 130

longitudinal and rotary motion and having | rocking motion, whereby to reciprocate said 10
its intermediate portion offset laterally from | valve both longitudinally and laterally of
the axes of its ends, an element carried by | the valve seat,
said piston having sliding connection with | To testimony whereof I hereunto affix my
5 said offset portion of the rod and serving | signature in the presence of two witnesses
to rock said rod, and a stationary member | HUGH L. McDONALD,
having an inclined cam slot operatively in | Witness:
gaging said offset portion and serving to re- | JOHN G. NEVILLE,
ciprocate said rod simultaneously with the | JAMES McLENNAN.
